UNITED STATES PATENT OFFICE.

DAVID TURCOTT, OF BELOIT, WISCONSIN, ASSIGNOR TO P. B. YATES MACHINE COMPANY, OF BELOIT, WISCONSIN, A CORPORATION OF WISCONSIN.

TURNING MACHINE.

Application filed August 4, 1923. Serial No. 655,555.

My invention pertains to wood-turning and similar machines, and relates more especially to improved mechanism for facilitating the introduction of the work into the machine in position to be acted upon by the revolving knife-blades.

To enable those skilled in this art to have a full and complete understanding of the invention and its various structural and functional advantages, in the accompanying drawings forming a part of this specification a desirable and preferred form of the invention has been illustrated in detail, like reference characters being employed for the same parts throughout the several views.

In these drawings,—

Fig. 1 is a front elevation of the new machine with certain parts omitted for greater clearness in illustration;

Fig. 2 is a vertical cross-section, on an enlarged scale, on line 2—2 of Fig. 1;

Fig. 3 is a vertical cross-section on line 3—3 of Fig. 1, the parts being illustrated on an enlarged scale;

Fig. 4 is a horizontal section through the tail-stock, on line 4—4 of Fig. 3;

Fig. 5 is a vertical section through the tail-stock, on line 5—5 of Fig. 3;

Fig. 6 is a vertical section on line 6—6 of Fig. 5;

Fig. 7 is an enlarged sectional detail;

Fig. 8 is a face view of the spirally-threaded, clamp-actuating member of the tail-stock;

Fig. 9 is a longitudinal, vertical section through the head-stock of the appliance; and

Figs. 10 and 11 are sections showing the locking mechanism permitting manual opening and closing of the jaws of the tail-stock.

Referring to these drawings, it will be perceived that the machine includes a main frame 21 of irregular and appropriate form and shape.

The appliance includes a laterally-movable table or support 22 (Figs. 1 and 2), the lower frame portion 25 of which is supported at each end by a back link 23 rockingly mounted on the main frame at 24 and pivotally connected to the part 25 at the point 26, such frame 25 being also supported at each end at the front by a link 27 fulcrumed at 28 and rockingly connected to the frame at 29. A pair of links 31, one at each end, is pivoted to the part 25 at 32, and is

connected at 33 to the upper end of a corresponding arm 34 fastened to a horizontal front shaft 35 rockingly mounted in bearings 36, 36, and equipped with a manipulating handle 37.

As the handle 37 is rocked back and forth, the table 22 and the parts which it carries will have a forward and rearward movement in a substantially horizontal plane. This table and its mounting is old and well known and forms no direct part of the present invention.

The main frame is equipped with three bearings 41, 42 and 45, accommodating a shaft 43 on which the cutter knives (not shown) are designed to be mounted, such shaft being adapted to be rotated in any approved manner, as by means of a belt pulley 44.

In order that the rapidly-revolving knives may be more or less encased when the work is moved away from them, the structure is provided with a hood or cover composed of a stationary part 51 and a portion 52 hinged thereto at 53 and provided with an arm 54 connected by a link 55 to an arm 56 on an appropriately-mounted rear rock shaft 57, which is supplied with another arm 58 cooperating with a bar 59 extended through a hole in the main frame, and having a beveled end 61, the bar passing beneath and coacting with a suitably-mounted roller 62, the front end of such bar being pivotally connected to the movable table 22 at the point 63.

When the table 22 moves forwardly, the bar 59 travels with it, and after a certain extent of such travel it permits the arm 58 to rise and the hood section 52 to rock downwardly more or less, encasing or enclosing the revolving knives. When the table is moved rearwardly the beveled end of the bar engages a roller on the arm 58, and during its continued rearward movement it causes the opening or upward rocking of the hood element 52, all as will be readily understood.

The table 22 is supplied with a head-stock characterized as a whole 64, and an adjustable tail-stock similarly designated by the reference numeral 65.

Referring first to the head-stock, which is held in position on the table by the screws or bolts 66, 66, it will be seen that it incorporates two ball-bearings 71 and 72 for a shaft 73 equipped at its protruding end with a suitably-shaped, toothed center 74.

The shaft 73 has a worm-wheel 75 keyed thereto and designed to be rotated by an upright worm 76 on the upper portion of a shaft 78 extending through a sleeve or collar 77 (pivotally supported on rod 104 hereinafter described) and having a bearing 79 for its lower end on a yoke 81 rockingly mounted on a lower shaft 82 revoluble in a pair of bearings 83 and 84, shaft 82 being operatively connected to the shaft 78 through intermeshing bevel gears 85 and 86.

Shaft 82 is equipped with two pulleys 87 and 89 and an intermediate, loose pulley 88, crossed and straight belts 91 and 96 cooperating with these pulleys and with a pulley 92 on an upper main shaft 93 rotatable in bearings 94 and 95 and equipped with a cone pulley 98 by which it may be driven, a suitable belt-shifter 97 being provided for manipulation of the belts as may be required.

The enlarged portion of the head-stock includes a casing 101 enclosing the worm and worm-wheel and equipped with a cover plate 102, projecting inwardly from which is a bearing 103 (Figs. 2 and 9) slidably accommodating a rod or shaft 104 pivotally connected at 105 with the bearing or collar 77 and equipped with a coiled, expansion spring 106 between the rear end of the bearing 103 and suitable nuts 107 on the threaded end of the rod. It will be perceived that this spring, by acting through the rod, normally yieldingly holds the worm 76 in intermeshing operative engagement with the teeth of the worm-wheel 75.

A bent arm or lever 108 fulcrumed on a stud 109 on the inside of the cover plate 102 is rockingly connected with the bearing or collar 77 in alinement with the axis 105, and it has a depending end adapted to ride on the top face of a slightly curved cam bar 111 fulcrumed or rockingly mounted on the main frame at 112 and resting on a roller 113 carried by the table 22.

The construction of these coacting elements is such that when the table 22 is rocked forwardly, carrying with it the worm and worm-wheel, the lever 108 by co-operation with the cam bar 111 and against the action of spring 106 pushes the worm forwardly, slightly out of mesh with the worm-wheel, thus temporarily interrupting the rotation of the spindle 73 and the stock center 74.

The head-stock spindle 73 also has keyed to it a gear 121 in mesh with a smaller gear 122 on a shaft 123 revoluble in a pair of alined bearings 124 and 125 in the head-stock and operatively connected to a shaft 126 through a suitable or appropriate coupling 127 (see Fig. 9).

This shaft 126, as is clearly illustrated in Fig. 5, extends through and is revoluble in a bearing 131 in the lower portion of the tail-stock 65, the main supporting body 133

of the latter being adjustably secured by screws 132 to the table and providing a bearing 130 for an intermediate, cylindrical member 134 having a square hole 135 extended through it for the accommodation of the stock to be worked on.

A plurality of screws 136, 136 fasten a ring 137 against one face of the element 134, such ring having a central, square aperture in register with the corresponding aperture 135, the tail-stock being provided with a cover plate 138 fastened against the face of the member 133 by screws 139, such plate having a cylindrical opening provided with an oil-tight packing for the accommodation of the ring 137, which necessarily revolves with the part 134, being rigidly fastened thereto by the screws 136.

Inside of this tail-stock structure the ring member 137 is equipped with a gear 141 in mesh with a driving pinion 142 keyed to the shaft 126 and having a hub occupying a round hole in the lower portion of the plate 138.

It will be seen therefore that the rotation of the shaft 126 is transmitted through the intermeshing gears 142 and 141 to the two elements 137 and 134, which are fastened together by the screws mentioned, and which are revolvably mounted in the bearing 130.

The tail-stock includes also a round member 151 with a central aperture 152 therethrough of general square shape, the element 151 being held securely against the face of the part 134 by a number of screws 153, this end of the tail-stock having a suitably shaped and apertured cover-plate 154 held against the part 133 by suitable screws 155 and having an oil-tight bearing on the outer cylindrical surface of the part 151, the latter having two opposed grooves or slots 156, 156, adapted to accommodate the angular stock clamping members 157, 157, each of which inside of the tail-stock has an outstanding part 158 with a short, spirally-arranged thread on the outer portion only of its inner face.

A ring 159, having on one face a spiral screw-thread or scroll 160, is revolvably mounted on the outer cylindrical face 161 of the member 134, not accommodated in the bearing 130, and between the parts 159 and 130 the element 134 has an outstanding, separating rib 162.

A ring-gear 163, by means of suitable screws, is fastened against the inner face of the screw-threaded member 159, and, as is shown in Fig. 4, this gear is in mesh with another gear 164 on a shaft 165 revoluble in a bearing 166 in the member 133, the protruding end of the shaft being fitted with a manipulating handle 167.

It will be understood that the work-clamping jaws 157, 157 may be made to expand and contract by turning the handle 167 pro-

vided the part 134 and its associated elements are temporarily prevented from rotating. It is necessary, therefore, to use some locking means in order to make the handle 167 effective for the desired adjustment of the jaws.

Accordingly, shaft 126 has a collar 171 (Figs. 9, 10 and 11) keyed thereto, such collar or sleeve around its periphery being provided with a pair of radial recesses or cavities 172.

On the table I provide a block 173 having a bearing 174 accommodating a sleeve 175 equipped with a shoulder 176, between which and a similar shoulder 177 in the part 173, a coiled spring 178 encircling the sleeve is interposed, such spring tending to force the sleeve to the right as the parts are viewed in Figs. 10 and 11, the sleeve having a longitudinal slot 179 into which the end of a pin 181 in the part 173 projects, permitting the sleeve to have a limited longitudinal play in its bearing, the extreme end of the sleeve having an enlargement 182 limiting the movement of the sleeve to the left.

The sleeve has a bearing 183 for a rod 184 with a tapered end 185 adapted to enter any one of the locking recesses 172, the pin or rod having a larger head 186 at its opposite end accommodated in a larger cavity 187 in the sleeve, with a coiled, expansion spring 188 received in such larger cavity and interposed between the head 186 of the pin and a plug 189 closing the end of the hole, the latter being held in place by a set-screw or cross-pin 191.

The appliance includes in addition a front, fixed shaft 192 supported on the main frame at 193, 193, and carrying at an end a split block 194 in which is mounted an upstanding rod 195 with a clamp 196 at its upper end adjustably holding a stop rod or pin 197.

Projecting upwardly from the shaft 192 I employ two brackets 198, 198, each fitted at its upper end with a clamp 199 carrying a rearwardly-inclined rod 201 having a work-rest 202 at its end.

The spindle 73, as is shown in Figs. 1 and 9, is supplied with a demountable or detachable form 203 which determines the shape of the work turned out by the revolving knives, various styles of products being capable of production by the use of suitably-shaped elements 203.

The operation of the appliance occurs practically as follows:

Assuming that the machine is in operation and that it is desired to insert a piece of work to be operated upon by the revolving knives, the operator pulls forwardly on the handle 37, thereby shifting the table 22 and the parts which it carries in the same direction.

The table having reached its foremost

position in alignment with the work rests 202, 202, the constantly-rotating worm 76 will have become separated from the complementary worm-wheel 75, so that the rotation of the latter and the parts which it ordinarily turns will cease, this separation of the worm and worm-wheel occurring even though both are mounted on the table which has been shifted to forward position.

Owing to the breaking of this driving connection between the worm and worm-wheel, if it were attempted to release the work-clamping jaws 157, 157 by the turning of handle 167, this could not be accomplished because the parts geared to such handle are now freely rotatable, and they would, therefore, revolve under such circumstances if the locking mechanism described had not become operative.

When the table moved forwardly, the end of sleeve 182 struck the abutment 197, pushing the sleeve and its locking pin 184 toward the recessed collar 171. If one of the recesses 172 was in register, or substantially in register, with the pin 184, the latter directly entered it and locked the shaft 126 against turning. If no such recess was directly in alignment with the pin as the pin was pushed out, the pin could ride on the periphery of the collar, due to the yield of spring 188, until the next recess came in position, whereupon the expansion of the spring forces the pin into locking position.

The parts thus having been locked against rotation, the operator turns the handle 167, which revolves the threaded scroll-element 159 relatively to the jaws, thereby expanding them and releasing the formerly clamped work, which can now be readily removed. A new piece of work having been rested upon the seats 202, 202, the operator turns the handle 167 in the opposite direction and contracts the clamping jaws onto the work so that it is firmly engaged, it being understood, of course, that the work is properly applied to the spiked head center 74.

When the table is then shifted rearwardly by manipulation of the handle 37, the shaft 126 is automatically unlocked and the worm and worm-wheel are automatically brought into operative re-engagement.

It is to be understood that as the table swings forwardly into inoperative position, the cover 52 comes down over the knives to shield the workman, and that when the table swings rearwardly into operative position the cover opens up to expose the knives for action on the stock.

Those skilled in this art will have no difficulty in understanding the advantages accruing from the use of such an appliance, and they will understand that the invention is not limited and restricted to the precise and exact structural details presented, since these may be modified within comparatively

wide limits without departure from the heart and essence of the invention and without the sacrifice of any of its substantial benefits and advantages.

5. I claim:

1. In a turning appliance of the character described, the combination of means to clamp the stock to be turned, constantly-rotated driving means, means operatively connecting said driving means with said clamping means to revolve the latter, means to shift said connecting means and said driving means relatively to one another to establish and break the operative relation between the two, means to lock said clamping means automatically and positively against turning when said connecting means is moved out of engagement with said driving means, and manually-actuated means to contract and expand said stock-clamping means when thus locked.

2. In a turning appliance of the character described, the combination of a rotatably-mounted supporting-means, expandible and contractable stock-clamping jaws mounted on and rotatable with said supporting-means, threads on said jaws, a spirally-threaded scroll-element rotatable on said supporting-means and having its thread in operative engagement with said jaw-threads, a gear fixed to and rotatable with said scroll-element, a pinion in mesh with said gear, a handle to turn said pinion, a gear fixed to said supporting-means, a pinion to rotate said latter gear, means to shift said supporting-means and the jaws into and out of stock-turning position, and means to automatically lock said supporting-means, gear and its pinion against turning when said supporting-means and its stock-clamping jaws are in non-stock-turning position whereby the jaws may be contracted or expanded by rotation of said handle while the parts are locked as specified, said locking means comprising a collar rotatable with said second pinion and having a series of locking recesses, a support shiftable with said supporting-means and its jaws, a locking-pin slidable in said support and adapted to enter any one of said collar recesses, and a substantially-stationary abutment in the path of travel of said pin adapted to project the latter into one of the locking recesses of the collar when the supporting-means and jaws are retracted into non-stock-turning position.

3. In a turning appliance of the character described, the combination of a table, means to shift said table into and out of stock-turning position, means on said table to clamp the stock, means to rotate said stock-clamping means having a collar with a series of recesses, a support on said table, a locking-pin slidable in said support and adapted to enter any one of said collar-recesses, and a substantially stationary abutment in the path of travel of said pin adapted to project the latter into one of the locking recesses of the collar when the table is retracted into non-stock-turning position.

4. In a turning appliance of the character described, the combination of a table, means to shift said table into and out of stock-turning position, means on said table to clamp the stock, means to rotate said stock-clamping means having a collar with a series of recesses, a support on said table, a spring-retracted sleeve slidable in a bearing in said

support, a locking-pin slidable in a bearing in said sleeve and adapted to enter any one of said collar recesses, a spring tending to slide said locking-pin toward said collar, and a substantially stationary abutment in the path of travel of said sleeve adapted to project the yielding locking-pin into one of the locking recesses when the table is retracted into non-stock-turning position, the locking-pin spring permitting the pin to yield temporarily until one of the recesses comes into register with the pin.

5. In a turning appliance of the character described, the combination of a rotatably-mounted supporting-means, expandible and contractable stock-clamping jaws mounted on and rotatable with said supporting-means, threads on said jaws, a spirally-threaded scroll-element rotatable on said supporting-means and having its thread in operative engagement with said jaw-threads, a gear fixed to and rotatable with said scroll-element, a pinion in mesh with said gear, a handle to turn said pinion, a gear fixed to said supporting-means, a pinion to rotate said latter gear, means to shift said supporting-means and the jaws into and out of stock-turning position, and means to automatically lock said supporting-means, gear and its pinion against turning when said supporting-means and its stock-clamping jaws are in non-stock-turning position whereby the jaws may be contracted or expanded by rotation of said handle while the parts are locked as specified, said locking means comprising a collar rotatable with said second pinion and having a series of locking recesses, a support shiftable with said supporting-means and its jaws, a locking-pin slidable in said support and adapted to enter any one of said collar recesses, and a substantially-stationary abutment in the path of travel of said locking-pin adapted to project the latter into one of the locking recesses of the collar when the supporting-means and jaws are retracted into non-stock-turning position.

6. In a turning appliance of the character described, the combination of a rotatably-mounted supporting-means, expandible and contractable stock-clamping jaws mounted on and rotatable with said supporting-means, threads on said jaws, a spirally-threaded scroll-element rotatable on said supporting-means and having its thread in operative engagement with said jaw-threads, a gear fixed to and rotatable with said scroll-element, a pinion in mesh with said gear, a handle to turn said pinion, a gear fixed to said supporting-means, a pinion to rotate said latter gear, means to shift said supporting-means and the jaws into and out of stock-turning position, and means to automatically lock said supporting-means, gear and its pinion against turning when said supporting-means and its stock-clamping jaws are in non-stock-

turning position whereby the jaws may be contracted or expanded by rotation of said handle while the parts are locked as specified, said locking means comprising a collar 5 rotatable with said second pinion and having a series of locking recesses, a support shiftable with said supporting-means and its jaws, a spring-retracted sleeve slidable in a bearing in said support, a locking-pin slidable in a bearing in said sleeve and adapted to enter any one of said locking recesses, a spring tending to slide said locking-pin toward said collar, and a substantially stationary abutment in the path of travel of 10 said sleeve and adapted to project the yielding locking-pin into one of the locking recesses of the collar when the parts are retracted into non-stock-turning position, the locking-pin spring permitting the pin to yield temporarily until one of the recesses 15 of the collar comes into register with the pin.

7. In a turning appliance of the character described, the combination of a table, a head-stock on said table, means to rotate said head-stock, means on said table adjustable toward and from said head-stock to clamp the stock to be turned, means to shift said 20 table to carry the stock associated with said head-stock and clamping means into and out of stock-turning position, a shaft, means to rotate said shaft, gearing between said shaft and stock-clamping means, whereby the rotation of the shaft is transmitted to said

clamping-means, means to expand and contract said stock-clamping means to grasp 35 and release the stock, and means to lock said shaft automatically against rotation when said table is moved out of stock-turning position to permit operation of said contracting and expanding means. 40

8. In a turning appliance of the character described, the combination of a table, a revoluble head-stock on said table, revoluble expandable and contractable means on said table adjustable toward and from said head- 45 stock to clamp the stock to be turned, means to shift said table to carry the stock associated with said head-stock and clamping means into and out of stock-turning position, constantly-rotating driving means, 50 means to expand and contract said stock-clamping means to grasp and release the stock, means to connect said head-stock and stock-clamping means to said driving means to cause their rotation when the stock is in 55 turning position and to automatically break such driving connection when the stock is in non-turning position, and means to lock said stock-clamping means automatically in definite positions against rotation to permit operation of said contracting and expanding means when said table is moved out of stock- 60 turning position.

In witness whereof I have hereunto set my hand.

DAVID TURCOTT.
